UNITED STATES PATENT OFFICE

2,541,158

FIREBOX COVER LIFTER

Robert E. Gardiner, Richmond Heights, Mo., assignor to Majestic Manufacturing Company, St. Louis, Mo., a corporation of Missouri

Application November 17, 1947, Serial No. 786,433

2 Claims. (Cl. 294—12)

1

The present invention relates generally to stove lid or firebox cover raising devices, and more particularly to a simple firebox raising device which is readily detachable.

Coal and wood burning stoves, as manufactured back through the years, have included a firebox over which is disposed a cover of unitary or segmental construction. When coal is burned, it may be applied after lifting a cover segment. However, when wood is employed as a fuel, it is difficult, if not impossible, to insert the usual length fire sticks through a segmental cover opening, and, hence, it is desirable to raise the whole firebox cover. Heretofore, integral firebox cover raising or lifting handles have been provided, but these are objectionable because such a device forms an obstruction above the cooking plane of the stove, and such device often is too hot to handle for raising or lifting the firebox cover without the use of some protective device for the hand.

An object of the present invention is to provide a novel firebox cover raising device which overcomes the deficiencies of devices for a similar purpose heretofore used.

Another object is to provide a novel firebox cover raising device which is readily removable and insertable.

Another object is to provide a novel firebox cover raising device which is readily removable, yet which, when in operative position, will remain so disposed.

Another object is to provide a novel firebox cover raising device which is formed for engagement with a firebox cover in order to relieve an individual of the necessity of holding the cover in raised position while placing firewood, or the like, in the firebox.

Other objects are to provide a novel firebox cover raising device which is simple in construction, which is inexpensive to make, which is effective for its intended purpose, which is adapted for use without breakage for years, and which may be readily employed by a user for its intended purpose with minimum instruction.

The foregoing and other objects and advantages are apparent from the following description, taken in connection with the accompanying drawing, in which:

Fig. 1 is a side elevational view of a firebox cover raising device formed in accordance with the teachings of the present invention;

Fig. 2 is an end elevational view thereof looking toward the handle portion;

2

Fig. 3 is a cross-sectional view on the line 3—3 of Fig. 1;

Fig. 4 is a fragmentary front elevational view of a portion of a stove with the present device operatively engaging the firebox cover, the device and the cover being shown in raised positions, the former engaging a hook, in broken lines; and

Fig. 5 is a fragmentary plan view of the same stove portion showing the firebox cover and the raising device in place.

Referring to the drawing more particularly by reference numerals, 10 indicates generally a firebox cover raising device formed in accordance with the teachings of the present invention. The device 10 is preferably constructed of a metal rod 12 of circular cross section, which includes a cover aperture insertion portion 14, a body portion 15, and a handle portion 16. The portion 14 is twisted out of the plane of the portions 15 and 16 about fifteen degrees, as is clear from Figs. 2 and 3. The portions 14 and 16 are bent downwardly from the body portion 15, considering Fig. 1, the former shown at about ninety degrees and the latter at about seventy-five degrees. However, these angles are not critical.

A heavy helical spring 18 of barrel form is disposed about the free end of the handle portion 16 to form a handle, being welded to the handle portion 16 at 19 and 20. The spring 18 terminates at its free end in a loop 21.

Referring to Figs. 4 and 5, there is shown a portion of a stove 24 including portions of a splash-back 25, a cooking top 26, and a firebox 27. An integral firebox cover 28 closes the top of the firebox 27 and includes an aperture 29, or well if preferred, drilled near its rear edge. A hook 30 is secured to the splash-back 25 near its upper left hand corner, as shown.

In use, the portion 14 of the device 10 is inserted in the aperture 29 of the cover 28, as shown in full lines in Figs. 4 and 5, and the cover 28 pivotally opened by raising the device 10. The device 10 may be engaged over the hook 30 to hold the cover 28 in the position shown in Fig. 4, so that both hands of an individual may be free to place firewood, or the like, in the firebox 27.

It is to be noted from Fig. 5 that, when the device 10 is engaged in the aperture 29 of the cover 28, the handle portion 16 and the spring 18 are disposed at about fifteen degrees to the vertical. Hence, the effective weight of the handle portion 16 and the spring 18 maintain the device 10 in position, since this force is conveyed

to the aperture engaging portion 14, causing it to frictionally engage the wall of the aperture 29 to insure its remaining in place.

The present device 10 is removable and may be kept on the hook 30 through the loop portion 21. However, the device 10 may be left on the stove 24, if desired, and will not become too hot inasmuch as the handle portion 16 and the spring 18 extend away from the stove 24, and there is only line contact between that segment of the portion 15 engaging the stove top 26 and the engaged stove top. Heat passing along the rod 12 towards the spring 18 is sufficiently dissipated.

It is apparent that there has been provided a device which fulfills all the objects and advantages sought therefor.

It is to be understood that the foregoing description and the accompanying drawing have been given by way of illustration and example. It is also to be understood that changes in form of the elements, rearrangements of parts, and substitution of equivalent elements, which will be obvious to those skilled in the art, are contemplated as within the scope of the present invention, which is limited only by the claims which follow.

What is claimed is:

1. A firebox cover raising device comprising a rod member including a cover engaging portion, a body portion, and a handle portion, said cover engaging and handle portions being disposed angularly to said body portion, both said cover engaging portion and said handle portion extending downwardly from said body portion when said device is operatively engaging a firebox cover, 35

said cover engaging portion being bent laterally at an angle to the handle portion so that said handle portion is at an angle to the vertical when the cover engaging portion is operatively engaging a firebox cover.

2. A firebox cover raising device comprising a rod member including a cover engaging portion of circular cross section, a body portion, and a handle portion, said cover engaging and handle portions being disposed angularly to said body portion, both said cover engaging portion and said handle portion extending downwardly from said body portion when said device is operatively engaging a firebox cover, said cover engaging portion being bent laterally at an angle to the handle portion so that said handle portion is at an angle to the vertical when the cover engaging portion is operatively engaging a firebox cover, said cover engaging portion being rotatable in a receiving aperture in a firebox cover to permit lateral movement of said device after a firebox cover is raised so as to engage the device at the intersection of the handle and body portions with a provided hook for supporting a firebox cover in raised position.
